DESIGN FOR A TABLE LAMP

Jack Gordon, Los Angeles, Calif.

Application September 23, 1946, Serial No. 133,530

Term of patent 3½ years

(Cl. D48—20)

To all whom it may concern:

I, Jack Gordon, a citizen of the United States, residing in Los Angeles, in the county of Los Angeles and State of California, have invented a new, original, and ornamental Design for Table Lamp, of which the following is a specification, reference being had to the accompanying drawing, forming a part thereof.

The drawing shows a perspective view of a table lamp showing my new design, the dominant features of which are illustrated in full lines.

I claim:

The ornamental design for a table lamp, as shown and described.

JACK GORDON.
